(57) **CLAIM**

The ornamental design for a split-grip baseball bat trainer as shown and described.

DESCRIPTION

FIG. 1 is a front, top perspective drawing of one embodiment of a split-grip baseball bat trainer showing our new design;

FIG. 2 is a front, bottom perspective drawing of a split-grip baseball bat trainer showing our new design;

FIG. 3 is a front view thereof;

FIG. 4 is a back view thereof;

FIG. 5 is a right-side view thereof;

FIG. 6 is a left-side view thereof;

FIG. 7 is top view thereof; and,

FIG. 8 is a bottom view thereof.

The broken lines shown in the drawings depict portions of the split-grip baseball bat trainer that form no part of the claimed design.

1 Claim, 5 Drawing Sheets
